UNITED STATES PATENT OFFICE.

EDGAR F. PORTER, OF PELLA, IOWA.

AUTOMATIC VACUUM-CUP HOG-OILER.

1,316,970.

Specification of Letters Patent. Patented Sept. 23, 1919.

Application filed April 28, 1919. Serial No. 293,312.

To all whom it may concern:

Be it known that I, EDGAR F. PORTER, a citizen of the United States, and resident of Pella, in the county of Marion and State of Iowa, have invented a certain new and useful Automatic Vacuum-Cup Hog-Oiler, of which the following is a specification.

The object of my invention is to provide a hog oiler of simple, durable and inexpensive construction, of the type having a vertical reciprocating rubbing post or bar adapted to operate a vacuum cup feed device so constructed and arranged that upon the first operation of said rubbing post a full charge of oil will be delivered to the post, and upon subsequent operations only a small charge will be delivered until the post has been allowed to stand without operation for some little time.

A further object is to provide a tank supporting structure of simple and novel structure.

Still a further object is to provide such a device so arranged that it may be readily and easily mounted on an ordinary support, or removed therefrom.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a front elevation of a hog oiler embodying my invention.

Fig. 2 shows a side elevation of the same.

Fig. 3 shows a vertical sectional view taken on the line 3—3 of Fig. 1.

Fig. 4 shows a horizontal sectional view taken on the line 4—4 of Fig. 3; and

Fig. 5 shows a vertical sectional view taken on the line 5—5 of Fig. 1.

In the accompanying drawings I have used the reference numeral 10 to indicate generally the base, which may be in the form of a casting having a pair of upwardly extending parallel ears 11. At the rear part of the base is a bracket member 12 designed to be bolted to an upright 13.

At the forward part of the base is a pan-shaped member 14 for holding surplus oil that may drop off the rubbing bar herein-after mentioned.

Mounted on the upper part of the support 13, preferably by bolts, is an oil reservoir

15, having flanges 16 to receive the bolts 17. Extending forwardly from the lower part of the oil reservoir 15 is a horizontal flange 18, through which is extended a hole 19. At the forward end of the flange 18 is an upwardly extending supporting bracket 20, having a shoulder 21 in its forward part, as illustrated in Fig. 3.

Extending transversely across and resting upon the upper surface of the reservoir 15 is a bar 22 which extends substantially beyond the sides of said reservoir and has downwardly extending flanges 23 designed to engage the outer surfaces of the reservoir 15 near the upper edge thereof to hold the bar 22 against any longitudinal movement. The bar 22 may be secured to the reservoir 15 by screw bolts 24, if desired.

Extending downwardly within the reservoir 15, from the central portion of the bar 22, is a cylindrical plunger member 25, shown in Fig. 3. Spaced from and surrounding the plunger member 25 on the under surface of the bar 22 is an inverted pan-shaped member 26, shown in Fig. 3.

I provide a rubbing bar 27, which may have substantially the shape of a half cylinder, provided on its forward surface with alternating overlapping ribs 28, inclined outwardly and upwardly from their overlapping ends, which are located near the forward vertical center of the rubbing bar 27.

At its lower end the bar 27 is formed with a downwardly and rearwardly extending tongue or strip 29 received between the members 11. The tongue 29 is provided with a vertically elongated slot 30, and a bolt 31 is extended through the ears 11 and the slot 30 in the tongue 29, as illustrated in Figs. 1, 2 and 5.

At the upper end of the rubbing bar 27 is an upward extension 32 extending slidably upwardly through the opening 19, as illustrated in Figs. 2 and 3.

Received within the reservoir 15 is an upwardly opening cup 33. Leading from the upper part of the cup 33 forwardly and through an opening 34 in the forward wall of the reservoir 15, and thence downwardly and outwardly to the forward surface of the rubbing bar 27, is a trough-shaped member 35 which is rigidly connected with the extension 32 in some suitable way, as by means of screws 36.

The plunger member 25 has extending through it a hole or passage 37 leading

from the lower part of the plunger upwardly and to the forward surface thereof to a suitable point for discharging to the trough 35, which inclines from thence forwardly and downwardly.

In the lower part of the cup 33 the wall of said cup is provided with an opening 38.

I provide for use with my improved hog oiler an oil or vermicide container comprising a cylindrical can 39, which in use with my device is inverted, as illustrated in Fig. 3. The container 39 has a cylindrical extension 40, which, when the container is in position for use, extends downwardly into the reservoir 15 and is designed to conduct oil or the like from the container 39 into the lower part of the reservoir 15.

The parts are so arranged that the lower end of the extension 40 is below the lower edge of the opening 34, so that the fluid oil or the like forms a liquid seal for preventing the escape of the contents of the container 39 except as the contents of the reservoir 15 are delivered to the rubbing bar 27.

25 The parts are also constructed so that when the rubbing bar 27 is in its normal lowered position the bottom of the cup 33 is considerably below the bottom of the plunger 25, and the bottom of the plunger 25 is at least slightly above the hole 38, so that the crude oil or other vermicide or contents of the container 39 and reservoir 15 will pass through the opening 38 into the lower part of the cup 33.

35 The container 39 is placed with the member 40 up, and filled therethrough. Thereafter it is inverted and supported on the bar 22 and the bracket 20. A yoke 41 may be extended over the container 39 and its 40 ends may be extended through the ends of the bar 22 and locked in place by means of wing nuts 42, for holding the container against accidental removal.

45 It will be obvious that the contents of the container 39 will flow down through the extension 40 until the reservoir 15 fills up to the lower end of the member 40, whereupon the liquid will form a seal and prevent the further discharge of such liquid from the 50 container.

When the hog or other animal comes to the device and rubs against the rubbing bar 27, it will be noted that said bar is capable of vertical reciprocation. When the rubbing bar is moved upwardly it carries with it the cup 33, the lower part of which will have been filled through the hole 38 with the vermicide or crude oil or other liquid. When the cup moves upwardly its contents 55 will be forced out through the passage 37 to the trough-shaped member 35, from whence the liquid will be discharged upon the upper front surface of the rubbing bar 27.

60 It will be noted that at the beginning of 65 the upward movement of the cup 33, the

opening 38 will be closed and no further supply of liquid will pass into the cup 33 while said cup is raised. If the animal continues to rub on the post for moving it up and down, it will be noted that after the 70 first discharge of the liquid from the cup 33 a very small additional supply of liquid will pass into the cup 33 until after the agitation of the rubbing bar is stopped for a sufficient period to permit the liquid to 75 flow in through the opening 38.

I find that a device of this kind is economical for the reason that when the rubbing bar is reciprocated there is first delivered to the bar a full charge of the liquid, and thereafter only a small charge is delivered upon each raising of the rubbing bar until the animal allows the rubbing bar to remain quiet for a considerable period. I am thus able to a considerable extent to avoid waste 85 of the oil or other contents of the reservoir 15.

With a device of this kind there is no danger of an animal moving the rubbing bar to position where there is a constant discharge from the reservoir.

The parts are of very simple and inexpensive construction, and the whole device may be readily and easily mounted on a post or supported anywhere in the feeding 95 yard.

The bar 22 furnishes a means for supporting the plunger member 25, and also for supporting and holding the container 39 in its proper position. The bracket 20 also assists in holding the container in position, and serves as a guard or protection for the trough-shaped member 35 which conducts the liquid from the passage 37 to the upper front surface of the rubbing bar. 105

The oil is held by vacuum to the required depth in the reservoir, and the vacuum cup holds enough to supply the rubbing bar at the first operation thereof, after which very little oil is supplied until the animal quits 110 rubbing.

Incidentally, the pan-shaped portion 14 of the base catches all the drippings off the bar, and this oil thus caught is applied to the under parts of the hog. 115

Some changes may be made in the construction and arrangement of the various parts of my improved hog oiler without departing from the essential spirit and purpose of my invention, and it is my intention to 120 cover by my claims any modified forms of structure or use of mechanical equivalents which may be reasonably included within their scope.

I claim as my invention:

1. A hog oiler comprising an upright member, a member projecting therefrom at the lower end thereof, a reservoir supported at the upper end of said upright, a rubbing bar mounted on said projecting member 130

- and said reservoir, for vertical reciprocation by an animal, a cup within said reservoir, having an opening in its wall near its lower portion, a liquid conducting device leading 45
 5 from the upper end of said cup to the upper end of said bar, and adapted to be reciprocated with the bar, and a plunger device supported on said reservoir and received in said cup, having an opening extended through it adapted to conduct liquid from the lower part of the cup to said liquid 50
 10 conducting means.
 10 through it adapted to conduct liquid from the lower part of the cup to said liquid conducting means.
 2. A hog oiler comprising an upright member, a member projecting therefrom at 15 the lower end thereof, a reservoir supported at the upper end of said upright, a rubbing bar mounted on said projecting member and said reservoir, for vertical reciprocation by an animal, a cup within said reservoir, hav- 55
 20 ing an opening in its wall near its lower portion, a liquid conducting device leading from the upper end of said cup to the upper end of said bar, and adapted to be reciprocated with the bar, a plunger device sup-
 25 ported on said reservoir and received in said cup, having an opening extended through it adapted to conduct liquid from the lower part of the cup to said liquid conducting means, a bar for supporting said 65
 30 plunger, having arms projecting beyond said reservoir, and a receptacle supported on said projecting ends and having a cylindrical member extending into said reservoir.
 35 3. A hog oiler comprising an upright member, a member projecting therefrom at the lower end thereof, a reservoir supported at the upper end of said upright, a rubbing bar mounted on said projecting member and 70
 40 said reservoir, for vertical reciprocation by an animal, a cup within said reservoir, hav- 75
 45 ing an opening in its wall near its lower portion, a liquid conducting device leading from the upper end of said cup to the upper end of the rubbing bar.
 50 per end of said bar, and adapted to be re- 45
 55 ciprocated with the bar, a plunger device supported on said reservoir and received in said cup, having an opening extended through it adapted to conduct liquid from the lower part of the cup to said liquid 50
 60 conducting means, and a bracket on said reservoir, extending upwardly and forwardly therefrom, adapted to serve as a support for a receptacle and as a guard for said liquid conducting device at the upper end 55
 65 of said rubbing bar, said bracket having an opening in it to receive the upper end of the rubbing bar.
 70 4. A hog oiler comprising an upright member, a member projecting therefrom at 60 the lower end thereof, a reservoir support- 70
 75 ed at the upper end of said upright, a rub-
 80 bing bar mounted on said projecting mem-
 85 ber and said reservoir, for vertical recipro-
 90 cation by an animal, a cup within said res-
 95 ervoir, having an opening in its wall near its lower portion, a liquid conducting device leading from the upper end of said cup to the upper end of said bar, and adapted to be reciprocated with the bar, a plunger device 70
 100 supported on said reservoir and received in said cup, having an opening extended through it adapted to conduct liquid from the lower part of the cup to said liquid con- 75
 105 ducting means, a bar for supporting said 80
 110 plunger, having arms projecting beyond said reservoir, a receptacle supported on said projecting ends and having a cylindrical member extending into said reservoir, and a 85
 115 bracket on said reservoir, extending up- 80
 120 wardly and forwardly therefrom, adapted to serve as a support for the receptacle and as a guard for said liquid conducting device at the upper end of said rubbing bar, said bracket having an opening in it to receive 85
 125 the upper end of the rubbing bar.

Des Moines, Iowa, April 9, 1919.
